CECIL CUTLER AND DANIEL FRANCIS MORAND, OF SYDNEY, NEW SOUTH WALES,
AUSTRALIA; SAID CUTLER ASSIGNOR OF HIS RIGHT TO ERNEST VEREY, OF
SYDNEY, NEW SOUTH WALES, AUSTRALIA.

LOOSE-LEAF BINDER.

1,346,180.

Specification of Letters Patent. Patented July 13, 1920.

Application filed October 25, 1917. Serial No. 198,383.

To all whom it may concern:

Be it known that we, CECIL CUTLER and DANIEL FRANCIS MORAND, subjects of the King of Great Britain and Ireland, residing, respectively, at 183 Pitt street, Sydney, New South Wales, Australia, have invented new and useful Improvements in Loose-Leaf Binders, of which the following is a specification.

- 10 This invention relates to binders for carrying loose leaves of a ledger or other book, and it has for its object to provide for the carrying of the loose leaves in such a way that while the binder is open they may be removed and replaced with great facility in normal or "offset" order; further to provide for the locking of the leaves in the binder when same is closed without disturbing their normal and offset relation; further 20 to provide for the expansion of the binder to adapt it for carrying a small or a large number of leaves as required; and further to provide for the resting of the leaves in a binder while lying open in such a manner 25 that said leaves will rest apart at an opening, so insuring accessibility, and retain the relative positions in which they are placed in the binder by the user without risk of falling together, whereby manipulation of 30 the leaves is facilitated when same are being handled for the insertion, checking or correction of entries thereon, and whereby also maintenance of the proper opening for reinstatement of leaves so removed is assured. 35 The invention has for additional objects the mounting of the binder posts in the binder covers in such a way as to obviate risk of accidentally demounting the post and dislocating the leaves when the posts are being set 40 to close the binder or to permit it to be spread open for book-keeping purposes.

As is usual, the binder is constituted of a back cover and a front cover which are respectively fitted with flexibly attached stub or butt portions, and "posts" therein carry the contained leaves and secure the covers together. In a binder made according to this invention each leaf is eye-holed and notched symmetrically on one stub edge and 50 may be set in the binder either in normal or in offset position as required. Four or more posts are used; of these two at least are "lock posts," and two at least are "riding posts". The former serve for locking

up the leaves in the binder, and the latter 55 for carrying the leaves when the binder is open. All the posts are sectional, that is to say made up of a plurality of short lengths with socket and spigot screwed ends for securing any two or more of the sections together to form the necessary length and for mounting the posts in the back stub. One section of each of the riding posts is bent 60 or curved. The stub bar on the back cover is a solid or tubular metal bar fitted with 65 tapped sockets into which the screwed lower end of the posts are insertable. The sockets are not essential, as the posts may be screwed into tapped holes in the bar. The locking stub bar on the front cover is a hollow or tubular bar having holes drilled 70 through it in register with the sockets in the back cover bar. In this tubular bar a locking slide controllable by a screw key of known type is fitted for the purpose of sliding the bar to pinch the posts in the locking stub bar to secure the front cover stub on the binder posts and fix the leaves in the binder. The sockets for the lock posts are short and 75 are threaded with a left hand thread, the male ends of the short lower sections of the lock posts being left-threaded to correspond with the socket thread. The sockets for the riding posts, which are located preferably on either outer side of the lock post 80 sockets, are long sockets with a right hand thread, the lower ends of the riding posts having corresponding male right-hand threads formed on them. The object of 85 reversely threading the lock post sockets and right hand threading the riding post sockets respectively is, firstly to insure the placing of the proper posts in the respective sockets, and secondly to obviate accidental unscrewing of the lock posts at an intermediate joint 90 when they are being unscrewed out of the back cover stub bar. When the binder is in use the bent riding posts permit the book to be set with the covers spread apart angularly with the leaves on either side of the 95 opening leaning against one cover or the other as the case may be, with a clear opening space between the left hand and right hand blocks of said leaves, so that a book-keeper using the binder may separate the 100 two blocks of leaves at the proper opening and may then remove either or both of the two leaves facing the opening for the inser-

tion of entries thereon, and return such leaf or leaves to the binder in the proper position therein. Each leaf is formed with four equidistant notches in the stub edge of it 5 registering with the post centerings, and consequently the leaves on which the entries have been made may be offset from normal position (the lock posts or the upper sections thereof being first removed to free the 10 leaves) by straddling the alternate pair of notches on the bent riding posts, thereby facilitating ready identification of and reference to the leaves which have been removed and replaced in offset position and enabling 15 ready checking of entries made thereon before finally replacing them in normal order. If the leaves were set in the binder with posts passing only through the notches there would be a risk, particularly when the 20 binder is not closed very tightly, of a leaf or leaves becoming displaced and some or all of them falling out of the covers.

Our loose leaf binders are provided with four posts; of these two are lock posts and 25 two are riding posts. Provided the leaves are appropriately holed and notched three or more lock posts and three or more riding posts may be used, but for all practical purposes two lock posts and two riding posts suffice. When the lock posts are removed, 30 this disposal of the leaves in normal or offset order as required is effected by dropping them into one position or the other with their stub notches straddled on the riding 35 posts. Two of the three eye-holes in the leaf stubs, when the leaves are placed normal in the binder, are always in register with the lock post sockets, while a different pair of the leaf eye-holes is similarly in 40 register with the lock posts when the leaf is in offset position in the binder, and therefore when the lock posts are threaded in and screwed home all the leaves in whatever position they may be are securely locked in the 45 covers.

In the accompanying drawings, Figure 1 is a perspective view of our binder in the closed locked position, with all the leaves set normally; Fig. 2 is a similar view showing 50 the key inserted to manipulate the pinching bar, the riding post extensions screwed on, and two leaves offset; Fig. 3 is a plan view of a blank leaf showing in full lines in normal position on the posts and in dotted lines the offset position thereon; Fig. 4 is a perspective view of the binder supported on a stand with the covers spread apart and the leaves separated into two blocks, one of 55 which rests against either cover respectively, two leaves being shown offset in the right hand block; Fig. 5 is an elevational view of one of the lock posts; Fig. 6 is an elevational view of one of the riding posts; Fig. 7 is a perspective view of the back cover stub bar;

and Fig. 8 is a broken plan view of the front 65 cover stub bar with pinching bar and locking screw fitting.

A is the back cover, B its stub which may be united to its rigid flat portion by a flexible union piece C. D is the front cover, E 70 its stub, and F its flexible portion uniting the stub to the flat portion. G is the back stub bar which is mounted in or on the stub B. In the case of a four-post binder, it is fitted with two short sockets HH tapped 75 left-hand, and also, disposed symmetrically on either side of the sockets HH two longer sockets JJ, which are tapped right-hand. K is the hollow front stub bar, L a slide post pinching bar within it, and M a screw which 80 may be turned by a key N or like instrument to set the position of the bar L in the hollow stub bar K. The bars K and L are pierced with holes k and l registering with the post sockets HH and JJ. O are the 85 lock posts, and P are the riding posts. Q are the lowermost detachable sections of the lock posts terminating at the foot in a left hand thread nipple R, and at the head in a right hand tapped socket; all the spigot 90 and socket joints marked S are right hand connections. T are tommy holes. U are blank book leaves. V eye-holes in the stub margins thereof, and W notches symmetrical and alternating with the eye-holes V. 95

In a four post binder there are ordinarily but not necessarily three eye-holes V and four notches W. X are knobs on the outer ends of the riding posts. Y is a book stand which may be adjustable for angular set or 100 position apart, of the pillows y. Z are the bent sections of the riding posts.

The manner of using the binders is as follows:—In the locked position, Fig. 1 the upper sections of the lock posts O (see Fig. 5) 105 are screwed on and the key N has been turned to pinch the posts between the slide bar L and the stub bar K (see Fig. 8) thus fastening the cover stubs B and E tightly on the leaves U, with the two binding posts O 110 passed through two of the eye-holes V of the leaves U and the riding posts set in two of the notches W of the leaves U. In this locked position the leaves may be all in normal position as shown in Fig. 1 or some of them may be offset (see Fig. 2). The lock posts and riding posts so locked in the binder are made up of an appropriate number of 115 sections (see Figs. 5 and 6) to suit the number of leaves and consequent thickness of the 120 charged binder.

To make ready for using the binder the bent sections Z and the outer extension sections and the knob ends X of the riding posts are screwed (right hand) onto the 125 standing sections thereof, as shown in Fig. 2. The binder while still closed as in Fig. 2, is then set up in a book stand or book rest

such as Y (Fig. 4). Then the key N is turned to release the posts from the front stub E, and the book is spread open as shown in Fig. 4. The lock posts O are then screwed 5 out of their sockets HH. The leaves are thus left free to be slid along the riding posts, to be lifted out, or to be restored to position as required. The leaves on either side of the opening may be disposed leaning against the 10 one cover or the other as required and placed in normal or offset order or rearranged in any serial order, or reversed back to front as may be found desirable to facilitate the purpose of the user. The closing of the binder 15 is a reversed operation.

The lock posts are made up of a bottom left hand nipple and as many sections as the thickness of the binder demands. These sections are screwed tightly together, the 20 tommy-holes T being provided for tommy rods to effect this fastening. The tightness of the intermediate joints, thus secured, holds them secure against accidental slackening back when the posts are being screwed 25 home on the base (left hand) thread and in the unscrewing movement to remove the lock posts from their sockets HH, the tendency is to tighten up the intermediate joints. There is, therefore, no risk of leaving a portion 30 of either of the lock posts in its socket or disconnecting the sections in the screwing or unscrewing movement. So long as any two posts remain standing in the binder the loose leaves therein are held in register and 35 the other posts may therefore be rapidly inserted through the appropriate eye-holes or stub notches in the leaves or withdrawn as required without disturbing the leaves.

What we claim as our invention and desire 40 to secure by Letters Patent is:—

1. A loose leaf binder comprising in combination, a binder member, a plurality of riding posts mounted on said member, said 45 posts being bent intermediate their ends so that said ends are disposed angularly to each other, a second binder member independent of and unconnected with the first member, movably mounted on said riding posts by means of apertures through which said posts 50 pass, and means carried by the second binder member for adjustably locking the same to the posts at varying distances from the first member.

2. A loose leaf binder comprising in combination, a binder member, a plurality of riding posts supported by said member, said 55 posts being bent intermediate their ends so that said ends are disposed angularly to each other, a second binder member mounted on 60 said posts, and means between said binder members for holding the same spaced apart a variable distance.

3. A loose leaf binder comprising in combination, a binder member, a plurality of 65 riding posts carried by said member, said

posts being bent intermediate their ends so that said ends are disposed angularly to each other, at least one locking post carried by said binder member, a second binder member mounted on said riding and locking posts, 70 and means carried by the second binder member for locking the same to said locking post.

4. A loose leaf binder comprising in combination, a binder member, a plurality of 75 riding posts mounted in said member, said posts being bent intermediate their ends so that said ends are disposed angularly to each other, a plurality of locking posts also mounted in said member insertible in and 80 removable from the same at will, a second binder member mounted on said riding and locking posts, and means carried by the second binder member for locking the same to the locking posts. 85

5. A loose leaf binder comprising in combination, a binder member, a plurality of riding posts supported by said member, each post comprising a plurality of sections, an intermediate one of which is bent so that its 90 ends extend angularly to each other, a second binder member mounted on said posts, and means between said binder members for holding the same spaced apart a variable distance. 95

6. A loose leaf binder comprising in combination, a binder member, a plurality of threaded sockets carried thereby, a plurality of riding posts having threaded connection with said sockets, each post comprising a 100 plurality of sections having screw threaded connection one with another, an intermediate one of said sections being bent so that its ends extend angularly to each other, a second binder member mounted on said 105 posts, and means between said binder members for holding the same spaced apart a variable distance.

7. A loose leaf binder comprising in combination, a binder member, provided with screw threaded sockets, a plurality of locking posts having screw threaded connection with said sockets insertible in and removable from the same at will, a plurality of riding posts mounted in said member, a second 110 binder member mounted on said locking and riding posts, and means carried by the second binder member for locking the same 115 to said locking posts.

8. A loose leaf binder comprising in combination, a binder member, a plurality of 120 sockets carried by said member and provided with left hand screw threads, a plurality of locking posts, each comprising a plurality of sections connected together by right hand 125 screw threaded connections, the lowermost section having a left hand screw thread to engage the corresponding threaded socket on the binder member, a plurality of riding posts mounted in said binder member, a 130

second binder member mounted on said locking and riding posts, and means carried by the second binder member for locking the same to said locking posts.

- 5 9. A loose leaf binder comprising in combination, a binder member, a plurality of locking posts carried by said binder member and insertible in or removable from the same at will, a plurality of riding posts also
10 carried by said binder member, a second binder member mounted on said locking and

riding posts, and means carried by the second binder member for locking the same to both the locking and the riding posts.

In testimony whereof we have signed our 15 names to this specification in the presence of two subscribing witnesses.

CECIL CUTLER.

DANIEL FRANCIS MORAND.
